UNITED STATES PATENT OFFICE.

BENNI BISS AND LEOPOLD KOHN, OF NEW YORK, N. Y.

CURLING-IRON.

1,147,296.

Specification of Letters Patent. Patented July 20, 1915.

Application filed August 25, 1913. Serial No. 786,558.

To all whom it may concern:

Be it known that we, BENNI BISS and LEOPOLD KOHN, subjects of the King of Hungary, both residing at 431 East Sixty-fifth street, New York city, in the county of New York and State of New York, have invented new and useful Improvements in Curling-Irons, of which the following is a specification.

10 Our invention relates to a curling iron and has as its principal object the provision of a device for the purpose mentioned which shall promote the convenience of the user and avoid, if possible, the chance of 15 burning the user.

A second object of our invention is to provide a device in which the two portions between which the hair is clamped may be moved longitudinally with relation to each 20 other.

A further object of our invention resides in the particular arrangement and combination of parts hereinafter described.

In the accompanying drawing:—Figure 1 25 is a perspective view of a curling iron made according to our invention. Fig. 2 is a side elevational and Fig. 3 a bottom-view of the same. Fig. 4 is a sectional detail view on an enlarged scale, taken on the line 4—4 of 30 Fig. 2.

In the separate views the same part is designated by the same reference character.

Referring more particularly to the drawing, *a—a* are three sheet iron cylinders 35 which are mounted on round rods *b* and *d—d*, and which are connected by two semi-cylindrical pieces of sheet metal such as *y—y*, so as to form two grooves. The rods *b* and *d—d*, at one end, are integral with

40 the shank *c* and the shank *c* is pivotally connected with another shank such as *h*. The shank *h* also has integral therewith, at one end, the round rods *f* adapted to fit into the grooves *y—y* between the cylinders

45 *a—a* and the pivotal connection between the shanks *c* and *h* is such that the rods *f—f* may be forced into register with the grooves *y—y* whenever desired. It will be seen, moreover, that both the shanks *c* and *h* are 50 provided with handles *o—o* for the convenience of the user, which are on the opposite sides of the pivot *k* from the rods such as *d—d* and *f*.

Referring more particularly to Figs. 3 55 and 4, it will be seen that the shank *h* is provided with an aperture *r* in which is

mounted the rivet *k* which serves as a pivot for the shank *c*. Moreover, it will be seen that the shank *c* is provided with a slot or groove *g* through which the rivet *k* extends 60 so that the shank *c* is adapted to move longitudinally on shank *h*.

The shank *c* is provided with a pin *m* on which is pivotally mounted a shank *e* which carries an aperture through which 65 the pin *m* passes. It will be seen that the shank *e* is provided with a handle *o* and has a slot *g'* which is curved along a circular arc corresponding to that of the shank *e* which will also be seen to be curved. It 70 will be seen that the rivet *k* extends up through the slot *g'* and a washer *s* is provided which surrounds the rivet *k* within the slot *g'* so as to reduce friction when the shank *e* is moved relatively to the pivot *k*. 75 It will be seen also that the rivet *k* is provided with an enlarged head in order to retain and protect the washer *s*.

From the foregoing it will be seen that in using our device, the hair to be curled is 80 laid across the cylinders *a—a* and then the round rods *f—f* brought into register with the grooves *y—y* by operating the handles *o—o* on the shanks *c* and *h*. Then in order 85 to curl or wave the hair, the handle *o* on the shank *e* is operated by bending around to the left, so as to approach parallelism with the other two handles, the other two handles meanwhile being held close together. The operation of the shank *e* causes such 90 shank to move relatively to the pin *k* owing to the curved groove *g'* and consequently, also moves the shank *c* giving the relative longitudinal movement between the cylinders *a—a* and the rods *f—f*. 95

It will be understood that while we have shown and described the preferred form of our device, we do not wish to be limited thereto but contemplate all modifications and rearrangements thereof which are mechanically equivalent to the form shown and described herein. 100

Having thus described our invention, what we claim is:—

A curling iron comprising, in combination, two pivoted shanks, a pin-like member on which said shanks are pivoted, clamping portions attached to said shanks for clamping the hair to be curled, one of said shanks being provided with a longitudinally disposed slot into which said pin-member extends whereby it is adapted to move rela- 105 110 115

tively to its point of connection with the other of said shanks, and means for longitudinally shifting said shanks relatively to one another, said means including a curved shank pivoted to said slotted shank and also provided with a slot, said curved shank having its slot engaging the said pin-like member.

In testimony whereof we affix our signatures in presence of two witnesses.

BENNI BISS.
LEOPOLD KOHN.
